US0D1023684S

(12) **United States Design Patent** (10) **Patent No.:** **US D1,023,684 S**
(45) **Date of Patent:** **** Apr. 23, 2024**

(54) **FENDER FRAME OF A COOLER**

(71) Applicant: **Dometic Sweden AB**, Solna (SE)

(72) Inventors: **Samuele Meda**, Solna (SE); **Mikael Thelin**, Huddinge (SE); **Kingda Wang**, Zhuhai (CN); **Steven Elliott**, Varsity Lakes (AU)

(73) Assignee: **Dometic Sweden AB**, Solna (SE)

(**) Term: **15 Years**

(21) Appl. No.: **29/803,817**

(22) Filed: **Aug. 16, 2021**

Related U.S. Application Data

(62) Division of application No. 29/697,070, filed on Jul. 3, 2019, now Pat. No. Des. 927,938.

(57) **CLAIM**

The ornamental design for a fender frame of a cooler, as shown and described.

DESCRIPTION

FIG. 1 is a perspective view of a fender frame of a cooler showing our new design.

FIG. 2 is a front view thereof; and,

FIG. 3 is a front view thereof with the broken line disclosure of the handle and upper mechanism removed.

The broken lines are for unclaimed subject matter of the fender frame of a cooler.

1 Claim, 3 Drawing Sheets
